UNITED STATES PATENT OFFICE

2,194,134

MINE SHAFT EQUIPMENT

Edwin J. Berryman, Grass Valley, and John B. Newsom, Nevada City, Calif., assignors to Idaho Maryland Mines Corporation, San Francisco, Calif., a corporation of Nevada

Application December 7, 1936, Serial No. 114,620

2 Claims. (Cl. 187—96)

This invention relates to a device for resisting the rotation of a hoisting cable operating within a mine shaft and to a combination of such a device with a safety hood and skip.

5 It is a well-known fact that oftentimes stranded hoisting cables tend to twist when they are subjected to a load. In mining operations this twisting of cables gives rise to considerable danger and therefore any solution of this problem 10 is important.

When sinking a mine shaft in accordance with and by the method and apparatus disclosed in J. B. Newsom's pending application Serial No. 15,226, filed April 8, 1935, now Patent No. 2,065,725, 15 it is not feasible to install guides during the sinking operation. This is for the reason that the drill must be raised to the surface each time that a core ten or fifteen feet long has been drilled. It has therefore been found necessary 20 to provide some other means for resisting or preventing the rotation of cables used in hoisting cores and apparatus such as skips.

In general, the object of this invention is the provision of means for resisting the rotation of 25 hoisting cables operating within a mine shaft.

Another object of the invention is the provision of means for resisting the rotation of a hoisting cable operating within a mine shaft in combination with a safety hood.

30 Still another object of the invention is the provision of a device for resisting the rotation of a hoisting cable operating within a mine shaft in combination with a safety hood and a skip.

The invention possesses other advantageous 35 features, some of which with the foregoing will be set forth at length in the following description where that form of the invention which has been selected for illustration in the drawing accompanying and forming a part of the present 40 specification is outlined in full. In said drawing, one form of the invention is shown, but it is to be understood that it is not limited to such form, since the invention as set forth in the claims may be embodied in a plurality of forms.

45 Referring to the drawing:

Figure 1 is an elevation of a device embodying the objects of our invention and shown in its operative position within a mine shaft.

Figure 2 is a plan view of the device shown in 50 Figure 1.

Figure 3 is a section taken on the line 3—3 of Figure 1.

As shown in the various figures of the drawing, the objects of our invention may be embodied in a device comprising a horizontal frame

or plate 1 adapted to be accommodated within the shaft 2. Secured to the plate 1 is a block 3 provided with a plurality of sheaves 4 by means of which the device is supported from a cable 5. Formed on the upper face of the plate 1 are a plurality of spaced sets of lugs 6, to which are pivoted arms 7, the free ends of which carry pins 8 for supporting rubber tired wheels 9, such as air plane wheels. To each pin 8 is pivoted a forked arm 11, the inner end of which is free to move through an aperture formed in the angle iron 12 secured to the block 3. For the purpose of limiting the outward movement of the arm 11, its inner end is threaded and provided with a nut 10. Surrounding the inner end of the forked arm 11 is a coil spring 13, one end of which engages the shoulder 14 of the arm 11, while the other end engages the angle iron 12. From this construction it will be seen that the spring 13 urges the wheel 9 20 radially outward against the walls of the shaft 2.

In the drawing two diametrically opposed wheels 9 have been shown. At right angles to the wheels 9 are wheels 15 rotatably secured to brackets 16 bolted or riveted to the plate 1. Although the wheels 15 have not been shown as provided with means for permitting their radial movement with respect to the shaft as are the wheels 9, it is obvious that all four wheels may be constructed and made to operate in the same 25 fashion as the wheels 9. Furthermore, instead of providing two radially movable wheels, the device could be made to operate with two or more fixed wheels and one radially movable wheel, and instead of using four wheels as shown in the drawing, three spaced wheels could be made to 30 operate very satisfactorily.

Secured to the under side of the plate 1 is an upright member 17, which may be conveniently 35 made by bending a plate back upon itself in the fashion of a hair pin, so that its free ends are spaced as shown in Figure 3. The upright 17 is braced by means of struts 18 welded to the under side of the plate 1. Bolted to the lower 40 end of the upright 17 is a bail 19 of a skip 20. The upper periphery of the skip 20 is provided with diametrically opposed straps 21 to which are pivoted U-shaped latches 22 adapted to straddle the side portions of the bail 19 and thereby hold the bail in a fixed position with respect to the skip 20. In order to prevent the skip 20 from rocking in the plane of the paper as shown 45 in Figure 1, a block or stop member 23 is secured to the upright 17 in contact with the bail 19. The vertical distance between the rim of 50

the skip 20 and the plate 1 should be sufficient to permit an operator to stand upright on the upper rim of the skip.

It will be noted that when the latches 22 are 5 in the position shown in Figure 1, the skip 20, bail 19, and upright 17 have no relative motion with respect to each other and form in effect an integral structure. If therefore the hoist operator lowers the hoist too far, the skip cannot 10 tip over in the shaft, but remains upright, thereby holding the plate 1 in a horizontal position so that the operator is protected at all times.

The plate 1 serves as a safety hood for the operator standing on the skip while working 15 within the shaft and should be provided with a man hole 24 through which an operator may pass, and with a cover 25 for closing the man hole 24.

It will be noted that due to the traction of 20 the wheels 9 with the walls of the shaft 2, and particularly due to the fact that the wheels 9 are urged in frictional engagement with the walls of the shaft 2 by means of the springs 13, the rotation of the frame or plate 1 together with 25 any load which it may carry, such as the skip 20, due to any tendency of the cable 5 to twist, is resisted or entirely prevented.

Although our rotation resisting device has been shown in combination with a skip, it can of 20 course be used in combination with any other load, such as for example a core, drilling machine, or elevator cage.

If it is desired to use a single cable for sup-

porting the rotation resisting device instead of a block and tackle as shown in the various figures, the cable frame or plate 1 may be provided with a ball bearing swivel to which the cable can be secured. In that event, the twisting of 5 the cable is taken up by the swivel and the plate or frame 1 held stationary by means of the wheels 9.

We claim:

1. A device for resisting the rotation of a hoisting cable within a mine shaft and designed for free vertical travel therein, comprising: a safety plate; spaced wheels rotatably secured to said safety plate on horizontal axes and arranged for traction within the walls of said shaft; means for supporting said safety plate from said hoisting cable; a vertical support rigidly secured to and depending from said plate; a skip provided with a bail immovably secured to the lower end of said 20 vertical support; and a latch for holding said skip in a fixed relation with respect to its bail.

2. A device for resisting the rotation of a hoisting cable within a drilled mine shaft and designed for free vertical travel therein, comprising: a safety plate; spaced wheels rotatably secured to said safety plate on horizontal axes and arranged for traction with the smooth walls of said shaft; means for supporting said safety plate from said hoisting cable; a bail immovably secured to said plate; and a skip secured to said 25 bail.

EDWIN J. BERRYMAN.
